BOX STRAPPING MACHINE

Ralph E. Cruse, Oakland, Calif., assignor, by
mesne assignments, to Acme Steel Company of
Illinois, Chicago, Ill., a corporation of Illi-
nois

Application March 6, 1933, Serial No. 659,761
Renewed April 12, 1938

23 Claims. (Cl. 1—10)

This invention relates generally to machines for applying and securing straps to boxes, crates and the like, and more particularly to machines of this character which are adapted for use where it is not desirable to employ a binding element which entirely encompasses the box.

It is an object of the invention to provide a machine of the above character which will make possible the use of a flat metal ribbon as a strapping element, and which will attach this strapping element to the box in such a manner as to afford great strength.

A further object of the invention is to provide a machine which will apply a flat metal strap in such a manner as to avoid troublesome protruding portions or exposed strap ends. In this connection the invention is characterized by the fact that the ends of the strap, particularly as applied to citrus boxes, are tucked into the sides of the box.

Additional features or characteristics of the invention, which are desirable objects, will appear from the detailed description of the preferred embodiment illustrated in the drawings, but the following can be briefly enumerated: The machine has a cycle of operation of such a character as to make for high capacity, and this cycle is carried out automatically, or semi-automatically. Provision has been made for adjustments whereby the machine can be made to accommodate boxes of various sizes. A high degree of operating reliability is afforded, with respect to the percentage of straps applied by the machine which must be rejected in practice. In addition to tucking in the ends of the strap, after the strap has been secured to a box, the strap applied snugly to the sides of the box, thus facilitating subsequent handling. The tucking-in operation as provided for in my machine is performed simultaneously with the cutting operation, by the use of a relatively simple mechanism.

Referring to the drawings:

Figure 1 is an end view of a machine incorporating the present invention, certain parts being in cross section, and certain parts being removed for clarity.

Fig. 2 is a side elevational view of the machine illustrated in Fig. 1.

Fig. 3 is a detail in elevation, illustrating the strap supporting units, and the strap feed means, at the beginning of a cycle of operation.

Fig. 4 is a detail in elevation, illustrating the positions of the head assemblies, during the cycle of operation, and after the strap has been applied to a crate. A crate being strapped is also shown

in this figure, together with means for pressing down the lid of the crate.

Fig. 5 is a view similar to Fig. 4, but illustrating the positions of parts near the end of a cycle of operation, as the end of the strap is being fed to the strap applying device 104. The crate and the means for pressing down the crate lid, shown in Fig. 4, have been omitted.

Fig. 6 is a detail in elevation, showing the back side of one of the head assemblies, with certain working parts removed.

Fig. 7 is an end view of the apparatus as illustrated in Fig. 6.

Fig. 8 is a plan view illustrating certain parts carried by the base of my machine, for positioning a box to be strapped.

Fig. 9 is a cross sectional detail, illustrating certain elements utilized for feeding a flat metallic strap from the source of supply, in conjunction with one of the strap supporting units.

Fig. 10 is a cross sectional detail taken along the line 10—10 of Fig. 9, but also showing the pinion and associated parts for operating the feed rack, the track for slidably retaining the rack, and means for rotating the pinion.

Fig. 11 is a cross sectional detail, illustrating one of the strap supporting units and nailing heads carried by the head assembly upon the right hand side of the machine as viewed in Fig. 1, the parts being in positions occupied at the instant that a nail has been driven and the strap is being severed.

Fig. 12 is a cross sectional detail of the strap supporting unit incorporated in Fig. 11, but showing the cutter in a retracted position.

Fig. 13 is a detail, illustrating the strap supporting unit of Fig. 12, and with reference to Fig. 12, looking from the right to the left.

Fig. 14 is a detail in plan, of certain of the elements incorporated in the mechanism of Fig. 9, 40 namely the body of the strap supporting unit and element to which it is pivotally connected.

Fig. 15 is a detail, illustrating a portion of the head assembly, incorporated on the right hand side of the machine as viewed in Fig. 1, and 45 showing the strap supporting unit 104 latched in a cocked position.

Fig. 16 is a detail, illustrating a part of the mechanism for actuating the parts illustrated in Fig. 9.

Figs. 17 and 18 are details, in different operating positions, showing certain parts of the actuating mechanism for the head assemblies, which are carried by the main cross-head of the machine and which appear in Fig. 1.

Fig. 19 is a detail, illustrating a part of the clutch trip mechanism in the drive connection to the head assemblies.

Fig. 20 illustrates the clutch trip mechanisms 5 for the strap feeding means, the cross head being shown travelling upwardly and in position to trip the finger for setting the strap feeding mechanism in operation.

Fig. 21 is a detail illustrating trip mechanism 10 for the main drive clutch, to continue the cycle of operation after the strap applying and nailing operations have been performed.

Fig. 22 is a detail illustrating trip means, actuated by movement of box, for the main clutch.

15 In the cycle of operation of the machine illustrated in the drawings, the strap to be applied to a box is supplied from a reel or other suitable source of material. A suitable length of this strap is applied across the top or lid of the box, 20 with portions depending along the box sides. The depending strap portions are then nailed to the box, the strap is cut, and the ends tucked in.

To facilitate a proper understanding of the machine illustrated, the following detailed description has been divided by appropriate subtitles.

General arrangement

Referring first to Figures 1 and 2, the machine 30 consists of a suitable frame structure 10, which in this instance includes the side uprights 11 and 12, and base structure 13. In order to arrange boxes in proper position to receive a strap, I provide suitable box conveying and positioning means, indicated generally by numeral 14. Carried by the frame of the machine in a manner 35 to be presently explained, are the head assemblies 16 and 17. Since head assembly 16 includes certain elements which serve to feed the metallic strap from a source of supply, it can be termed a strap feeder head assembly. Similarly assembly 40 17 can be termed a strap gripper head assembly, as it includes a means or unit which serves to grip one end of the strap during the cycle of operation. Both of assemblies 16 and 17 also 45 include strap supporting units and nailing heads to perform the operations of applying and securing the strap to the box.

The operation of compressing the lid of the box 50 during the strapping operation, is performed by a presser 18, which is normally in an elevated position as shown in Fig. 1. In addition to the general arrangement just described, the operating parts of the machine also have connections to actuate or motion applying means, to secure 55 operation in proper sequence.

Box conveying and positioning means

Referring to Figs. 1 and 2 and 8, the box conveying and positioning means includes a pair of track elements 21 which are carried in a horizontal position upon lateral members 21a (Fig. 8) of the base 13. Cooperating with the track elements 21, there is an endless chain conveyor 22. This chain is carried by suitable sprockets 23 and 24, which in turn are carried by shafts 26 and 21. Suitable journals serve to support these shafts in horizontal position upon the frame of the machine. The upper run of chain conveyor 70 22 extends thru a channel 28, which is arranged intermediate the track elements 21. This chain is provided with spaced box engaging lugs, such as are known in the art. Drive means for the chain conveyor 22, and tripping means which is 75 preferably utilized, will be presently described

under the heading of "Actuating and drive mechanism".

To enable lateral positioning of the box to be strapped, I provide a guide strip 31 (Figs. 1 and 8) which has an inner vertical face, and which 5 is elevated with respect to the track elements 21 and 22. In order to adjustably support the guide strip 31, this strip is shown carried by threaded rods 32, which extend thru a side angle member 33. Lock nuts 34 on rods 32, serve to adjustably 10 fix rods 32 with respect to brackets 36, which in turn are secured to the side angle member 33. Adjacent the other side of the conveyor track there is a side angle member 37, similar to the angle member 22. This angle member serves to 15 support a guide strip 38, which is urged inwardly by compression springs 39. When a box is being moved by the conveyor chain 22 and is forced 20 between guide strips 31 and 38, it is evident that the box is constrained to assume a predetermined position, in conformance with the desired line of operation, and dependent upon the setting of guide strip 31.

Strap feeder head assembly

Referring particularly to Figs. 1 and 4, the strap feeder head assembly consists of a casting or plate 41 upon which its operating parts are secured. In order to afford a mounting for plate 41 which will permit certain required movements, I have shown a cross head 44 extending laterally across the machine between the frame uprights 11 and 12. Vertical standards or rods 46 (Figs. 1 and 6), mounted in the sides of the frame, are slidably engaged by the end portions 47 and 48 of 35 cross head 44. For vertically reciprocating the cross head 44, there are shown connecting rods 49, having their upper ends provided with pivotal connections 51 to the cross head guide portions 47 and 48. Compression springs 50 serve as 40 counterbalancing means for the cross head and its associated parts.

In order to form a connection between plate 41 and the cross head 44, a plate or guide 52 (Figs. 6 and 7) is shown fixed to the cross head portion 47, in such a position as to extend laterally across the machine. By means of slotted pads and retaining plates 53 and 54, plate 41 is slidably retained upon guide 52, in such a manner that limited sliding movements with respect to the cross 50 head 44 is afforded. The extent of such movement can be adjusted by varying the setting of stops 55.

As a part of the means which serves to feed a metal strap between the heads 16 and 17, slidably 55 carried by the lower edge of plate 41, there is a rack 56 (Fig. 10). This rack is engaged by a pinion 57 to effect its reciprocation, and this pinion in turn is journaled to a bracket 58 secured to plate 41. A groove 59 formed within rack 56 60 (Fig. 9), forms a passage or guideway for the metal strap. Pivottally mounted within groove 59 there is a dog 60, beneath which the metal strap may pass. Since this dog is set at an inclination and is biased downwardly, it will permit 65 movement of the strap beneath it only in one direction with respect to the rack 56.

Carried by the inner end of rack 56, there is a strap-supporting unit or device 61 (Fig. 9) which performs several functions, including retention of the strap, bending of the strap about a corner of the box, and cutting of the strap from the source of supply after the strap has been applied. This device includes a body formed of spaced plates 62 secured upon opposite sides of 75

spacer 63, together with a box engaging plate 64. Extending thru the body there is a relatively flat passage 65 for receiving the metal strap, and slidably secured to the outer end of the body (Figs. 9, 10 and 14) there is a cutter 66. The 5 blade of cutter 66 operates against an anvil 61, and the cutter is normally biased towards a retracted position, by compression spring 68. For connecting device 61 to the rack 56, I have shown 10 a member 69 which is slidably keyed to the inner end of rack 56, and which has a pivotal connection 70 with device 61 (Fig. 9). A coiled spring 71 associated with pivotal connection 70 serves 15 to normally bias device 61 from the position shown in Fig. 9, to the position illustrated in Figs. 1 and 3. Fixed within groove 59 adjacent the dog 60, there is a block 73 adapted to have a lost motion connection with member 69. Thus 20 secured to member 69 there is a bar 76, one end of which is provided with a lug 74 adapted to operate within a slot 75 afforded in block 73. A compression spring 77 is interposed between block 73 and dog 60, to urge this dog into engagement with the underlying strap. A rod 78 is loosely socketed in member 69 and block 73, and surrounding rod 78 there is a compression spring 79. A tension spring 80 (Figs. 4 and 5) serves to 25 normally bias rack 56 to a retracted position. One end of this spring is secured to pin 81, and the other end is anchored to bracket 82. An adjustable stop 83 carried by bracket 82 limits movement of rack 56 towards a retracted position.

Mounted upon the casing 41, there is a suitable 30 nailing head 86 (Figs. 4 and 5), which may include a conventional chuck having its two elements or jaws held together by spring 87, a tube 88 for supplying nails to the chuck, and a driving plunger 89. For actuating driving rod 89, there is shown a carriage 91, slidably mounted upon the upper edge of casting 41. Depending from carriage 91, there is a rigid portion 92 to which driving rod 89 is adjustably secured. Likewise 35 adjustably secured to depending portion 92, there is a rod 93, one end of which forms a hammer head 94 for striking cutter 66. Rod 93 is suitably guided in casting 41, and is biased in one direction, together with carriage 91, by compression spring 96. For reciprocating carriage 91, a journal 97 is shown mounted thereon, which is operatively connected to a linkage to be presently 40 described.

For a purpose to be presently explained, it is 45 desirable to provide means for latching the strap supporting unit or device 61 in the cocked position shown in Figs. 4 and 9. Thus referring to Fig. 4, a latch 98 is pivotally secured to plate 99, which plate overlies the nailing head and is secured to the main casting on plate 41. Latch 98 is biased in a clockwise direction (as viewed 50 in Fig. 4) against a fixed stop, and is adapted to engage a pin 100 mounted upon one side of the body of device 61 (as shown in Fig. 15).

Gripper head assembly

In certain respects the gripper head assembly 55 65 is similar to the feeder head assembly previously described, although it is intended to operate upon the free end of the metallic strap, and therefore does not include strap feeding means. Thus this head assembly includes a casting 101 (Figs. 4, 5 and 15) which is mounted upon the cross head portion 48 in a manner similar to the casting 41 for head 16, that is to afford limited sliding movement laterally of the machine. 70 Pivotal mounted to the inner and lower corner 75

of casting 101, there is a strap supporting unit or device 104, which is adapted to receive and grip the free end of the strap, supplied from the head assembly 16. This device includes a body formed of spaced side plates 106 (Figs. 11 and 12) and provided with a relatively flat anvil plate 107. Pin 108 serves to pivotally secure the device to casting 101, for movement thru at least 10 90 degrees, and a tension spring 109 serves the same in a counter-clockwise direction, as viewed in Fig. 4. Slidably secured to the outer ends of side plates 106, there is a cutter 110, the blade of which cooperates with an anvil edge 111. A dog 112 pivotally secured to plates 106, is provided with a finger 113, extending into a slot 114 provided in cutter 110. Therefore when the cutter 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 2). This motor is shown driving a counter shaft 132, thru a suitable belt or chain drive 133. Counter shaft 132 in turn serves to drive a shaft 134, thru pinion 136 and gear 137. Disposed upon shaft 134, there is a one revolution clutch 139, serving when engaged to rotate a pinion 141. This pinion in turn engages a gear 142 to drive shaft 143. Fixed to the ends of shaft 143, are the crank wheels 144 which are connected to the cross head 44 by connecting rods 49. Thus when shaft 143 makes one half a revolution from the position shown in Fig. 2, the cross head 44, together with the head assemblies 16 and 17, are lowered, and during a further one half revolution, these parts are raised. Two complete revolutions of clutch 139 are required for a complete cycle of operation of the machine.

When shaft 143 occupies the position shown in Fig. 2, it is at rest, and clutch 139 is disengaged. 20 The clutch when tripped rotates shaft 143 one-half a revolution and is then tripped to stop shaft 143. After head assemblies 16 and 17 have been lowered and the parts associated with the same have performed their functions, clutch 139 25 is again tripped to return the cross head to its initial elevated position.

Lever 147 is preferably actuated in coordination with movement of a box or crate in position for a nailing operation. Thus arranged in the 30 path of movement of the box to be strapped, (Figs. 2 and 22) there is a trip lever 151, one arm of which is connected to a link 152. The other end of link 152 is connected to one arm of an L-crank 153, the other arm of which is connected to the upper end of rod 154. The lower end of rod 154 has an abutment or foot 156, to latch under pin 156a on the lever 147. When trip lever 151 is depressed by the advancing end of a box to be strapped, the linkage just described 35 lifts rod 154, to actuate lever 147, thus tripping the clutch 139, to engaged position. At the completion of such a tripping operation, the foot 156 escapes by lever 147, thus permitting lever 147 to return to its original position.

40 This escapement results from engagement of a portion of clutch 139 (while the latter is rotating) with a plate 154a formed on the lower end of rod 154 so as to shift this rod to release pin 156a from engagement by foot 156. This permits clutch lever 147 to drop, stopping rotation of clutch 139 at the end of a single revolution of the latter. Thus the rotation of clutch 139, resulting from the swinging of lever 151 by a box, ceases at the 45 end of a single revolution of this clutch even though the lever 151 remains depressed by virtue of the box resting thereupon during the strapping operation.

For driving chain 22 to move successive boxes into position for the strapping operation, power 50 is transmitted from the drive shaft 134 through a sprocket 158 fixed on the latter, and a chain 159 which is trained about sprocket 158 and a sprocket 161, the latter being freely rotatable on the shaft 27. Rotatable motion is transmitted 55 from the sprocket 161 to the shaft 27 through a single-revolution clutch 162. The chain 22 is provided with box propelling lugs 22a which are uniformly spaced apart along the chain distances, each of which is equal to the distance which the 60 chain 22 is caused to travel by one revolution of clutch 162.

This clutch is of the ratchet release type and includes an arm 164 which is fixed on the shaft 27, a pawl 165 pivotally mounted on the end of 65 the arm 164, and a spring 166 (Figs. 2 and 8)

which urges the pawl 165 constantly towards engagement with a toothed ratchet wheel 167, the latter being formed integral with the sprocket 161 and rotated therewith continuously in the direction of the arrow placed thereon in Fig. 2. 5 The pawl 165 has a finger 165a extending laterally therefrom which is adapted to come into engagement with a trip arm 168 which is pivotally mounted at its lower end on the frame of the machine and is operably connected with a foot lever 169 through a rod 171, and L-lever 172, and a rod link 173. Interposed between the connection of rod 171 with L-lever 172 is a compression take-up spring 174.

As long as the pawl 165 is free to be urged by 15 the spring 166 into engagement with the teeth of the continuously rotating ratchet wheel 167 this pawl engages said teeth, causing the arm 164 carrying this pawl to rotate the shaft 27 with the ratchet wheel 167. The upper end of the trip arm 168 however is disposed in the path which the finger 165a of the pawl 165 takes whenever this pawl is thus rotating with the ratchet wheel 167. When traveling in this path to a certain point, the finger 165a engages the upper end of the trip arm 168, this camming the pawl 165 outwardly away from engagement with the teeth of the ratchet wheel 167, thus causing an immediate cessation of the transmission of rotary motion from the ratchet wheel 167 to the shaft 27. 30

The suddenness with which the shaft 27 thus stops rotating results from the considerable friction between a packed box B and the tracks 21 on which this box is resting as said box is being shifted into working position in the strapping machine by engagement with the rear face thereof of one of the lugs 22a of the chain 22, as shown in Fig. 2.

When the foot lever 169 is in normal inactive 40 position, as shown in Fig. 2, the upper end of the trip arm 168 is disposed so as to shift the pawl 165 into and hold it in its inoperative position, the latter being also shown in this figure. Upon the foot lever 169 being depressed, the trip arm 168 of the clutch 162 is swung toward the left from the position in which it is shown in Fig. 2, so as to move out from under the finger 165a on the pawl 165, thus releasing this pawl and permitting the spring 166 to snap the pawl into engagement with one of the teeth on the ratchet wheel 167, thereby initiating a single revolution of the shaft 27 by the clutch 162. 50

In order to return the trip arm 168 to its normal position so that it will function to stop the rotation of the shaft 27 at the end of a single revolution, the operator removes his foot from the foot pedal 169 after having depressed this to initiate said single revolution. 55

The clutch 162 is so adjusted that every time it 60 is thus thrown out automatically the chain 22 halts with one of the lugs 22a advanced just far enough to place a packed box B in the machine with the central partition 175 thereof properly located to have a strap nailed thereto as will be 65 made clear hereinafter.

From the above it is evident that during intervals when no work is being fed to the machine the motor 131 may remain in operation while the conveyor chain is at rest. If a box is now placed 70 upon the conveyor, and foot lever 169 depressed the conveyor operates to move the box to the box strapping position, after which the conveyor stops. Depression of trip lever 151 by the box now starts the machine in operation to perform 75

the strapping operation. After completion of the box strapping operations, lever 169 is again depressed to discharge the strapped box, and to deliver a new box to the machine.

5 To actuate parts carried by the head assemblies 16 and 17 (Fig. 1) mounted upon the cross-head 44, there is a shaft 191, carrying a double-armed lever 192. The arms of lever 192 are connected by links 193, to the upper arms of levers 194, 10 which are journaled to the cross-head 44 by studs 196. Likewise journaled to the studs 196, and rotatable with respect to lever 194, are the arms 197. Links 198 serve to connect these arms with the journals 97. Interposed between the lower 15 ends of levers 194 and arms 197, are yieldable take-ups, which can be constructed as follows: Upon each of the arms 197 (Figs. 17 and 18) there is a lug 199, engaging one end of a rod 201. Each of these rods slidably extends thru a lug 202, fixed to the lower arm of the associated 20 lever 194. A compression spring 203 is interposed between lug 202, and the thrust washer 204 fixed to the outer end of rod 201. Thus referring to Figs. 17 and 18, when each lever 194 is rotated 25 in a counterclockwise direction, force is transmitted to the associated link 198 thru the compression spring 203. In the event link 198 cannot follow the complete oscillating movement of lever 194, lost motion is taken up by the compression spring 203.

Before describing the remainder of the actuating mechanism for rotating shaft 191, it may be explained that upon rotating this shaft in a counterclockwise direction as viewed in Fig. 1, 30 journals 97 are moved together, or inwardly with respect to the machine. The manner in which shaft 191 is connected to journals 97, and also the provision of yieldable take-ups described above, makes it possible to continually rotate 40 shaft 191 in one direction.

Extending vertically of the machine (Fig. 1) there is a shaft 206, having its lower end connected to shaft 134, by suitable gearing 207. The upper end of this shaft is retained by a suitable journal 208 secured upon top of the machine frame, and the lower shaft and is carried by journal 209. Splined to shaft 206, there is a worm gear 211. This worm gear serves to drive a shaft 212, carrying a gear 213, which in turn engages 45 a gear 214, journaled to shaft 191. The drive from gear 211 to gear 213, is thru a one revolution clutch 216 of the ratchet tooth type, which is under the control of a lever 217. To operate the clutch control lever 217, I have shown a lever 50 218, connected to lever 217 by link 219. A bracket or standard 221 is mounted upon cross head 44, and serves to journal shaft 222, to which lever 218 is secured. Fixed to the rear end of shaft 222 (Fig. 19), there is a finger 223, 55 biased in a clockwise direction as viewed in this figure, by spring 224. A cam abutment 226 is fixed to the frame of the machine, and is arranged to engage and oscillate finger 223 in a counterclockwise direction, during the completion 60 of the downward stroke of the cross head 44. Movement of finger 223 by engagement with cam abutment 226, trips clutch 216 to engaged condition to effect rotation of shaft 191 one complete revolution, after which clutch 216 automatically disengages itself.

It has previously been explained that when the machine is started in operation, by tripping the main clutch 139, cross head 44 is moved to its lowermost position, where it comes to a position of rest, while certain operations take place.

Likewise following the completion of certain operations, the main clutch 139 is again automatically tripped to raise the cross head back to its original position. To perform this latter function, that is to effect automatic tripping of the main clutch 139 to raise the cross head to its original position, I provide mechanism as follows: Carried by one of the side upright structure members of the frame of the machine, there is a bracket 231 (Fig. 21), which serves to pivotally support an L-lever 232. Adjustably secured to one arm of L-lever 232, there is a rod 233, the lower end of which is connected to a pivotally mounted lever 234. The free end of lever 234 extends beneath the operating lever 147, for 10 the main clutch 139. Pivotedly connected to the other arm of L-lever 232, there is a member 236 having a cam surface. Pin 237 limits rotation of member 236 with respect to L-lever 232, in a clockwise direction as viewed in Fig. 21, but rotation in the opposite direction is permitted. A tension spring 238 biases member 236 in a clockwise direction. A pin 239 projects from that lever 15 196 which is upon the same side of the machine, so that as viewed in Figs. 1 and 21, when lever 20 194 swings to the left it passes over but rotates members 236. However when lever 194 swings back to the right, in tripping over member 236, L-lever 232 is turned to lift lever 234, and thus 25 actuate the main clutch control lever 147. It 30 should be noted in this connection that these operations take place while the cross head 44 is in a lowered position.

When the cross head 44 is raised to its upper position, means serves to actuate pinion 57, to 35 feed the strap between the two head assemblies 16 and 17, for a subsequent strapping operation. As representative of suitable means of this character, the upper end of a rack 241 has been shown pivotally connected with a member 246, which is 40 slidable within a suitable guideway 247 (Fig. 2). A lever 248, having a fulcrum 249 with the frame of the machine, has a link connection 250 with member 246. Journaled above the frame of the machine, there is a shaft 251, to which the crank 45 252 is fixed. A rod 253 serves to connect crank 252, with one end of lever 248. The alternative point of connection 250a, between lever 248 and link 250, permits making changes in the effective 50 leverage provided, thus facilitating making adjustments of the machine to varying conditions. Fixed to the other end of shaft 251, there is a bevel gear 254, engaging a bevel gear 261 upon the upper end of shaft 206. The drive between shaft 251 and gear 254, is thru a clutch 262. The 55 control lever 263 for this clutch, is operated by turning movement of a shaft 264. Thus referring to Fig. 20, a lever 266 fixed to shaft 264, is connected to lever 263, by link 267. Another lever 268 secured to shaft 264, is connected to the 60 upper end of a rod 269. The lower end of rod 269 is connected to one arm of a lever 271, which lever is pivotally carried by the main frame of the machine. The other arm 272 of this lever carries an abutment pin 273. This pin serves to 65 engage a finger 274, which is pivotally mounted concentric with the pivotal connection of lever 271, and which normally extends in the path of movement of cross head 44. Before cross head 44 has reached its uppermost position, engagement 70 with finger 274 turns this finger together with lever 271 in a counterclockwise direction viewed in Fig. 20, to trip the latch 262. When cross head 44 has reached the upper limit of its movement, it has passed the finger 274. When cross 75

head 44 moves downwardly, it trips past finger 274 without however rocking lever 271. Note that as shown in Fig. 20, a tension spring serves to bias lever 271 in a clockwise direction, and another spring biases finger 274 in a counter-clockwise direction.

It is evident from the above that before the cross head 44 reaches the upper limit of its movement, tripping of finger 274 trips clutch 262, thus 10 serving to effect one complete revolution of shaft 251, after which clutch 262 automatically releases itself. Obviously shortly after shaft 251 commences its rotation, cross head 44 will have reached its upper limit.

15 The means utilized for supplying nails to the nailing heads need not be described in detail, as such apparatus is well known in the art. However this means may include a nail pan 277, having a suitable drive connection to shaft 251, to 20 effect its oscillation.

General operation

Operation of my machine as a whole can now be described as follows: A box or crate, such as a 25 crate packed with citrus fruit having a bulged lid, is introduced into the machine, as by manually sliding it into a position upon the right hand end of the box conveying and positioning means 14 (Fig. 2). At that time motor 131 is in operation, but the conveyor chain 22 is stationary. Foot lever 169 is now depressed, with the result that 30 clutch 162 is rotated one revolution to drive conveyor chain 22 a sufficient amount to move the crate into proper position for a strapping operation, as shown in dotted lines in Fig. 2. In this connection note that the box engaging lugs on conveyor chain 22 should be so spaced that for the amount which this chain is driven, a lug near the rear end of the crate slides the crate to the 35 aforesaid strapping position. As the crate arrives in such a position, it engages trip lever 151, thus causing lever 147 to be raised to trip the main clutch 139. At this time it is presumed that a metallic strap 275 extends between the devices 40 61 and 104, shown more clearly in Fig. 3. The end of this flat metallic strap is retained by the dog 112, of device 104. Immediately upon tripping of the main clutch 139, rotation of shaft 143 causes the cross head 44 together with the head 45 assemblies 16 and 17 to move downwardly. As the head assemblies 16 and 17 are lowered toward the box, the strap 275 first contacts with the lid of the box, and then as the head assemblies are further lowered, devices 61 and 104 engage the 50 corners of the crate and are turned 90°, to the cocked positions shown in Fig. 4. The turning of devices 61 and 104, together with downward movement along the sides of the crate, bends the strap about the corners of the crate, to form 55 dependent portions, as shown in Fig. 4, in position to be nailed to the sides of the crate. Likewise as the head assemblies 16 and 17 are being lowered along the sides of the crate, the medial portion of the lid of the crate is engaged by the 60 presser member 18, to press down the lid, so that after the strap has been secured to the box, and the lid is released, the strap will be relatively tight. Immediately before the cross-head reaches its lowermost limit, the strap nailing 65 clutch 216 is tripped by engagement of cam abutment 225 (Fig. 19) with finger 223, which causes motion to be transmitted through lever 218 and link 219 (Fig. 2) to the clutch lever 217, thereby 70 commencing rotation of shaft 191. Rotation of this shaft through one revolution, while the head 75

assemblies 16 and 17 are in lowered position along the sides of the crate, rocks levers 194 in opposite directions and causes simultaneous movement of journals 97 inwardly. During the initial inward movement of journals 97, the castings or plates 41 move inwardly and are pressed against the sides of the crate. Thereafter, further inward movement of journals 97 actuate the nail driving plungers 89 (Figs. 4 and 5) to drive a nail through the depending portion of the strap. 10 When this nail driving operation has been completed, further inward movement of journals 97 causes hammer heads 94 to drive cutters 110 into the sides of the box, as shown in Fig. 11. With respect to the cutter carried by device 61, this 15 operation serves to sever the applied strap from the remainder of the strap supply, and at the same time serves to tuck the end of the strap into the side of the crate. With respect to the cutter carried by device 104, a short end portion of the 20 strap, which has been engaged by dog 112, is severed, and likewise the end of the strap is tucked or driven into the side of the crate. Simultaneously with operation of cutter 110, for device 104, dog 112 is rotated to released position (Fig. 25 11), to permit the severed end portion to fall. Likewise at this time member 117 is moved to a position shown in Figs. 11 and 12, so as not to retain the severed end portion.

The operations described above, while the head 30 assemblies 16 and 17 are in their lowered position, are completed during one-half revolution of shaft 191. During the remaining one-half revolution of shaft 191, journals 97 move outwardly to their 35 original positions, and at the same time plates 41 of the head assemblies are caused to move outwardly a certain amount out of engagement with the sides of the crate. Referring to Fig. 4, it will be noted that when devices 61 and 104 were turned 90° by contact with the corner of the 40 crate, they were latched in such position by means of latches 98. This provision makes it possible to raise the head assemblies without danger of devices 61 and 104 engaging the sides of the 45 crate. Shortly before shaft 191 completes one revolution, the main clutch 139 is tripped by engagement of pin 239 (Fig. 21) with member 236, which causes rod 233 and lever 234 to be raised. Tripping of the main clutch causes the cross-head to start upwardly towards its initial 50 position. Just before the cross-head reaches its uppermost position, latches 98 are released by engagement with fingers 120 (Fig. 12) to permit devices 61 and 104 to swing back to their normal position. Immediately thereafter clutch 262 is 55 tripped, by engagement of the cross-head with member 274 (Fig. 20) which in in turn transmits motion through rod 269, members 268, 266 and 267, to the clutch lever 263. Subsequent rotation of shaft 251 through one revolution transmits motion through crank 252, rod 253, lever 248 and link 250 (Fig. 2), to reciprocate rack 241. Rack 241, operating through pinion 57 (Fig. 16) serves to move rack 56 to the right (Fig. 5) to bring the devices 61 and 104 into engagement. 60 After such engagement, a further and final movement of rack 56, is accommodated by movement of lug 74 in slot 75 (Fig. 9). This further movement causes the end of the strap to enter device 104, beneath dog 112. Fig. 5 shows devices 61 and 104 in contact, immediately before final inward movement of rack 56 has forced the end of the strap into device 104. Now as rack 56 moves outwardly, responsive to upward movement of rack 241, the end of the strap is held by device 75

104, so that when rack 56 stops in its initial position, as shown in Fig. 3, the strap occupies a position preparatory to being applied to a succeeding box or crate, as shown in Fig. 3. The crate can 5 now be discharged from the machine, as by manually sliding it towards the left as viewed in Fig. 2, thus leaving the machine free to receive a successive crate.

It is evident that the invention is capable of a wide latitude of modification, both with respect 10 to the details of mechanical elements utilized, and with respect to the arrangement of these elements. Although it is desirable to have the machine automatic to the extent described, it is evident that for simplified and less expensive machines, some operations can be separately initiated by one or more clutch pedals to be actuated by the operator, to carry out the desired cycle. A simplified machine may also have provision 20 for raising the box, instead of lowering the head assemblies 16 and 17 to the box.

A desirable characteristic of the invention is that the length of the strap applied may vary somewhat in accordance with the height of the box or crate. Thus with an over-packed citrus crate, a longer length of strap is applied than to a medium or under-packed crate. This is because, while the devices 61 and 104 (Fig. 1) are always lowered to a definite height above the table, plate 121 will come to rest on the crate at varying level dependent upon the fullness of the pack. The additional lengths of strap which may be required for application to the crate is supplied by sliding of the strap through the groove 59 (Fig. 9) of rack 56, and through the strap supporting device 61, which necessitates a certain amount of sliding movement of the strap beneath the presser member 121, as the cross head 44 moves towards its lowermost limit. Thus there is no wastage of 40 strapping material and the strap is always nailed at a predetermined distance from the bottom of the box.

I claim:

1. In a machine for the strapping of boxes and the like, means for presenting a box in a box-strapping position, means for applying a strap across the upper face of the box with the end portions of the strap extending downwardly along two vertical sides, the strap being of a length insufficient to entirely encompass the box, means for nailing the end portions of the strap to the box, and means for tucking the ends of the strap into the box.

2. In a machine for the strapping of boxes and the like, means carrying a pair of strap supporting units, one of said units being formed to permit a metallic strap to be threaded thru the same from a source of supply and the other of said units being formed to receive and grip the end 55 of the strap, means for effecting relative movement of said units together and apart, to dispose a length of metallic strap between the same, and means for subsequently applying and attaching the strap to a box.

3. In a machine for the strapping of boxes and the like, means for supporting a box in a box strapping position, a pair of strap supporting units, one of said devices being adapted to have a metallic strap threaded thru the same and the other of said devices being adapted to grip and retain the end of the strap, means for bringing said units into engagement and for subsequently separating the same, whereby a portion of the strap is caused to extend between said units, said 70 units normally overlying the side corners of the

box and being capable of pivotal movement thru 90 degrees, and means for effecting relative movement between said units and said box, whereby said units are caused to assume positions along the sides of the box, and whereby during said 5 relative movement the strap is laid across the top of the box and bent around the corners thereof.

4. In a machine for the strapping of boxes and the like, means for supporting a box to be strapped, a strap supporting unit thru which a 10 metallic strap can be threaded, a second strap supporting unit adapted to receive and grip the ends of the strap, strap feeding means serving to position a length of the strap between said units, means for causing relative movement between 15 said units and the box whereby said units are caused to assume positions along the sides of the box, thereby causing the strap to be applied across the top of the box with portions depending along the vertical box sides, means for securing the 20 depending portions of the strap to the sides of the box, and means for severing the secured portion of the strap from the remainder thereof.

5. In a machine for the strapping of boxes and the like, means for supporting a box in a box 25 strapping position, a pair of head assemblies, each of said assemblies including a nailing head, strap supporting and severing means carried by one of said head assemblies, strap supporting and gripping means carried by the other of said head assemblies, means for transposing said head assemblies from positions overlying the box to positions along the sides of the box, and means for feeding a length of strap between said head 30 assemblies when said assemblies are in an elevated 35 position with respect to the box, whereby when said assemblies are transposed to positions along the sides of the box, a length of strap is applied across the top of the box with portions depending along the sides thereof, and means for actuating 40 said nailing heads when said head assemblies are in positions along the sides of the box.

6. In a machine for the strapping of boxes and the like, means for presenting a box in a box strapping position, a pair of head assemblies, 45 each of said head assemblies carrying a nailing head and a strap supporting unit, the strap supporting unit of one head assembly being adapted to receive and grip the end of a metallic strap, and the strap supporting unit of the other head 50 assembly being adapted to have a metallic strap threaded thru the same from a source of supply, feed means serving to position a length of strap between said units, means for transposing said head assemblies from positions overlying the box 55 to positions adjacent the sides of the box, whereby the strap is laid across the top of the box with depending portions extending down along the sides of the box, means for actuating said nailing heads to secure said depending portions 60 to the sides of the box, and strap severing means serving to sever the secured length of strap from the remainder thereof.

7. In a machine for the strapping of boxes and the like, a strap supporting unit comprising a 65 body, said body being formed to receive one end portion of a metallic strap, a dog carried by said body to releasably grip the end portion of the strap, a movable strap cutter carried by said body, and means for effecting release of said dog 70 when said cutter is moved to a position to sever the strap.

8. In a machine for the strapping of boxes and the like, a strap supporting unit comprising a body, said body being formed to afford a pas- 75

- sage thru which a flat metallic strap can be
threaded, a movable cutter carried by said body,
and means serving to support said device for
pivotal movements thru substantially 90 degrees.
- 5 9. In a machine for the strapping of boxes
and the like, a strap supporting unit comprising
a body, said body being formed to receive a flat
metallic strap, a movable strap cutter carried by
said body, means serving to support said device
10 for pivotal movement thru substantially 90 de-
grees, and releasable latching means serving to
retain said device in one limit of said pivotal
movement.
10. In a machine for the strapping of boxes
15 and the like, a reciprocable member, a second
member having a slideable lost motion connection
with said first member, said first member being
formed to permit a flat metallic strap to be
threaded therethrough, a strap supporting unit
20 pivotally secured to said second named member,
said strap supporting unit being likewise formed
to permit threading a metallic strap therethrough.
11. In a machine for applying straps to boxes,
25 a nail driving mechanism for driving nails
through strap material into the sides of boxes,
and a crimper blade associated with said nailing
mechanism for engaging the free end of said
strap and pressing the same into the sides of said
box.
- 30 12. In a box cover strapping machine the com-
bination of: means for receiving an overfilled box
with a cover disposed thereover; means for trans-
versely shaping a middle portion of said cover;
means for positioning a strap of thin sheet metal,
35 capable of penetration by a relatively small nail,
across the shaped portion of said cover with end
portions of said strap extending downward op-
posite upper portions of the box sides; means
for supporting nails in positions for piercing said
40 strap end portions; means for driving said nails
from said last mentioned means; and means co-
ordinately actuating said cover shaping and strap
positioning means, and, at the conclusion of the
functioning of the latter as aforesaid, actuating
45 said nail driving means to simultaneously nail
opposite end portions of said strap to sides of
said box.
13. In a machine for the strapping of boxes
and the like, the combination of: means for draw-
50 ing a strap under tension across the top of said
box including means for tightly gripping the ad-
vance end of said strap and means for yieldably
gripping said strap on the opposite side of said
box from said advance end; means for causing
55 relative vertical movement between said strap-
gripping means and said box to stretch said strap
across the cover of said box and downwardly ad-
jacent the sides of the latter; and means for se-
curing to the sides of said box those portions of
60 said strap disposed adjacent thereto while said
strap is thus stretched.
14. In a machine for the strapping of boxes
and the like, the combination of: gripping means
65 for holding a strip of strap material across a box
to be strapped, and gripping said material at
opposite ends of a given length thereof to permit
an additional amount of strap material to be
frictionally drawn through said gripping means;
means causing relative movement between said
70 box and said gripping means to wrap said strap
material about a portion of said box; and means
for securing to opposite sides of said box the op-
posite end portions of the length of said strap
material disposed adjacent to said box.
- 75 15. In a machine for the strapping of boxes
and the like, the combination of: means for sup-
porting a box; means spaced from said box for
gripping a length of strap material at spaced
points to hold said strap material in position
across said box; means causing relative move-
ment between said gripping means and said box
5 to draw said strap material about a portion of
said box and adjacent opposite faces of said box;
and means to secure to said opposite faces of said
box portions of said strap material adjacent
thereto.
16. In a machine for the strapping of boxes
and the like, the combination of means for sup-
porting a box to be strapped; a travelling carrier
15 for feeding the end portion of a continuous length
of strap material across said box; means for
effecting the wrapping of said portion of strap
material about the top and the upper part of the
sides of said box; and means for securing to op-
posite sides of said box the strap material ad-
20 jacent thereto.
17. In a machine for the strapping of boxes
and the like, the combination of means for sup-
porting a box to be strapped; a travelling carrier
25 for feeding a piece of strap material along the
axis of the material in a rectilinear path sub-
stantially parallel with the top of the box to a
position where said material is disposed across
said box; means for effecting the wrapping of
30 said strap material about the top and the upper
part of the sides of said box; and means for
securing to opposite sides of said box the strap
material adjacent thereto.
18. In a machine for the strapping of boxes
and the like, the combination of means for sup-
porting a box to be strapped; a travelling carrier
35 for feeding the end portion of a continuous length
of strap material across said box; means for ef-
fecting the wrapping of said portion of strap ma-
terial about the top and the upper part of the
40 sides of said box; means for securing to opposite
sides of said box the strap material adjacent
thereto; and means for cutting off the portion of
strap material so secured from the balance of
45 said material.
19. The method of strapping a box or the like
which comprises: drawing a piece of strap mate-
rial across a box and partway down the sides of
the latter and holding said strap material in
50 place, while unsecured to said box, by gripping
opposite ends of said piece of material and draw-
ing said material downward; and securing said
opposite ends of said material while thus held to
opposite sides of said box to retain said material
55 in place.
20. The method of strapping a box or the like
which comprises: drawing a piece of strap mate-
rial across a box and partway down the sides of
the latter and holding said strap material in
60 place, while unsecured to said box, by gripping
opposite ends of said piece of material and draw-
ing said material downward, and simultaneously
securing said opposite ends of said material while
thus held to opposite sides of said box to retain
65 said material in place.
21. The method of strapping a box or the like
which comprises: drawing a given length of a
continuous piece of strap material across a box
and partway down the sides of the latter and
holding said length of strap material in place,
70 while unsecured to said box, by gripping opposite
ends of said length of material and drawing
downward thereon; securing said length of mate-
rial to said box sides while so held; and severing
said length of material from the balance thereof.
- 75

22. The method of applying flat strap material to boxes which comprises: disposing a length of such material across a box and partway down the sides; substantially simultaneously nailing said material to the sides of said box; and substantially simultaneously crimping ends of said length of material into the sides of said box.

23. The method of applying flat strap mate-

rial to boxes which comprises: disposing a length of such material across a box and partway down the sides; and substantially simultaneously nailing said material to the sides of said box and crimping ends of said length of material into the sides of said box. 5
